UNITED STATES PATENT OFFICE.

JOHN A. SHARPS, OF BABLIN, WEST VIRGINIA.

SASH-BALANCE.

1,172,063.

Specification of Letters Patent. Patented Feb. 15, 1916.

Application filed June 23, 1915. Serial No. 35,898.

To all whom it may concern:

Be it known that I, JOHN A. SHARPS, citizen of the United States, residing at Bablin, in the county of Lewis and State of West Virginia, have invented new and useful Improvements in Sash-Balances, of which the following is a specification.

This invention relates to balances, the principal object of the invention being to provide simple and convenient means for adjusting the tension of the spring whereby the device may be employed for light or heavy sashes.

Another object of the invention is the provision of a device of this character which is so constructed that it may be conveniently attached to the under side of the window frame for operation in connection with the lower sash or attached to the framework of the building above the window frame for operation in connection with the upper sash.

Further objects of the invention will appear as the following specific description is read in connection with the accompanying drawing which forms a part of this application, and in which:—

Figure 1 is a front elevation of a window frame showing the device applied thereto and with the part of the frame broken away to show the position of the upper sash balance. Fig. 2 is a vertical sectional view through one of the spring casings. Fig. 3 is a plan view of one of the spring casings with the top plate removed.

Referring more particularly to the drawing 1 represents an ordinary window frame having upper and lower sashes 2 and 3 slidably mounted therein. As each sash is operated by a similarly constructed balance, the description of one will be sufficient. The balance for the lower sash 3 is secured to the under side of the upper portion of the window frame 1 as shown in Fig. 1 and consists of spaced plates 4 and 5 held together by screws 6 which pass through the spacing sleeves 7. The plates have journaled therein a spring winding shaft 8 which is shouldered at both ends as shown at 9 and 10, the latter shoulder being serrated or roughened to correspond with similar serrations formed on the inner side of the plate 5 as shown. Projecting beyond the shoulder 10 is a reduced threaded stem 11 upon which is

mounted a lock nut 12 and the outer end of the stem is provided with a kerf 13 for the reception of a screw driver.

Each plate 4 and 5 have surrounding the central aperture therein an annular groove 14 in which is received the edge of a tape drum 15 and between this drum and the shaft 8 is located a spiral spring, one end of which is attached to the shaft and the opposite end to the drum. The tape drum has secured to it and adapted to extend therefrom in opposite directions, a pair of tapes 16 or metallic bands which pass over pulleys 17 secured in brackets 18 at opposite sides of the frame and from thence to their attachment with opposite sides of the sash 3. The balance for the upper sash is constructed identically as described for the balance of the lower sash but is secured upon a vertical support above the window frame and behind the trim strip which in Fig. 1 is broken away. The pulleys 18 are secured upon brackets 19 above the window frame and the tapes running thereover, pass down through the apertures in the upper portion of the window frame and are attached at their terminals to the upper sash 2. The inner plate 4 of either balance is preferably provided with laterally extending ears 20 to receive securing devices for securing the balance to the window frame so that the outer plate does not have to be removed when it is desired to disconnect the balance from the frame.

When it is desired to adjust the tension of the spring a set screw or nut 12 is loosened and a screw driver or other similar instrument placed in the ear 13, the shaft 8 turned until the required tension is produced. The thumb nut 12 is then screwed up on the stem 11 binding the shoulder 10 against the inner side of the plate 5.

What is claimed is:—

1. A sash balance comprising a pair of spaced parallel plates, a shaft journaled in said plates, a spring secured to the shaft and surrounding the same, a drum surrounding the spring, said plates having grooves to receive the drum and said spring being secured at its opposite end to the drum, flexible members connected to the drum and to the sash.

2. A sash balance comprising a pair of

spaced parallel plates, a shaft rotatably mounted therein, said plates having an annular groove surrounding the shaft, a drum mounted to rotate in said groove concentric with the shaft, a spiral spring connected to the drum and shaft, a threaded extension on the shaft passing through the plate, means to rotate the shaft to wind the spring thereon and means threaded on the exten-

sion for clamping the shaft against one of the plates and preventing rotation thereof.

In testimony whereof I affix my signature in presence of two witnesses.

JOHN A. SHARPS.
